UNITED STATES PATENT OFFICE.

ABRAHAM R. BERRYMAN, OF EAST ALTOONA, PENNSYLVANIA.

RAIL-JOINT.

957,030.

Specification of Letters Patent.

Patented May 3, 1910.

Application filed August 12, 1909. Serial No. 512,485.

To all whom it may concern:

Be it known that I, ABRAHAM R. BERRYMAN, a citizen of the United States of America, residing at East Altoona, in the county of Blair and State of Pennsylvania, have invented certain new and useful Improvements in Rail-Joints, of which the following is a specification, reference being had therein to the accompanying drawing.

- 10 This invention relates to rail joints, and the object of the invention is to provide simple and effective means for connecting the confronting ends of two rails, whereby said rails cannot become laterally or vertically displaced relative to each other, thereby eliminating all danger of the derailment and wreck of rolling stock caused by the spreading or displacement of one rail relative to another.
- 20 Another object of this invention is to provide novel means for fastening bolts in the splice bars of the rail joint, the means being fully shielded and protected whereby it will be practically impossible for the fastened 25 end of the bolts to be sheared or cut off by wheel flanges, brake rigging or other parts that might contact with that part of the fastener which is exposed.

A further object of this invention is to 30 provide a strong and durable rail connection that allows for expansion and contraction, the rail connection being easily installed by unskilled labor and maintained in condition without the use of track-walkers or inspectors.

With the above and other objects in view the invention consists in the novel construction, combination and arrangement of parts to be hereinafter described and claimed.

40 In the drawing:—Figure 1 is a side elevation of the rail joint, Fig. 2 is a plan of the same, Fig. 3 is a cross sectional view, Fig. 4 is a perspective view of a portion of one of the splice bars, Fig. 5 is a plan of a 45 bolt forming part of the rail joint, Fig. 6 is a perspective view of a key, and Fig. 7 is an end view of the bolt.

In the drawing 1 denotes the abutting ends of two rails, said rails having the web 50 portions thereof provided with openings 2 and 3 and 4 designate splice bars bracing the sides of the rails 1.

The splice bar 3 is provided with a plurality of transverse openings 5 adapted to

align with the openings 2. The outer face of 55 the splice bar 3 is recessed adjacent to the openings 5 to provide oblong seats 6 for the heads 7 of bolts 8 adapted to extend through the openings 5 and 2. The opposite ends of the bolts 8 are provided with longitudinal 60 slots or openings 9 and the outer end walls of these openings are beveled, as at 10, for a purpose that will hereinafter appear.

The splice bar 4 has the outer vertical face thereof provided with an enlargement 11 65 approximately the same length and depth as the vertical outer face of the splice bar 4. The top and end edges of the enlargement 11 are beveled, as at 12 to deflect any object that might contact with the enlargement 11, 70 while the bottom edge of the enlargement 11 is parallel with a longitudinal off-set portion 13 of the splice bar 4, to form a longitudinal groove 14 to provide clearance for the split ends of keys, as will hereinafter 75 appear.

The splice bar 4 and the enlargement 11 are provided with transverse openings 15 80 adapted to align with the openings 2 and 5 and receive the slotted ends of the bolts 8. Each one of the openings 15 is intersected by a vertical groove 16 which aligns with the slot 9 of each bolt. In each groove is driven a tapering key 17 having the tapered end thereof provided with a head 18 and the lower end thereof split or slotted, as at 19. After the key is driven into the groove 16 and through the slot 9 of the bolt 8, the split end of the key which extends into the groove 14 is opened or spread to lock the 90 key in the enlargement 11 and the bolt 8. The spreading or opening of the split end of the key is accomplished by a suitable instrument.

It will be observed that when the keys 17 95 are driven into the slots 16 and 9 that the tapering keys draw the bolts into the openings 5, 2 and 15 and bind the splice bars 3 and 4 upon the sides of the rails. The heads 18 permit of a suitable instrument 100 gripping the keys 17 to withdraw the same from the enlargement 11, otherwise the keys are positively locked in engagement with the enlargement 11 and prevent the bolts and splice bars from becoming displaced.

While in the drawing there is illustrated what I believe to be a practical embodiment of my invention, still I would have it under-

stood that the structural elements thereof are susceptible to variations without departing from the spirit of the invention.

Having now described my invention, what 5 I claim as new, is:—

In a rail joint, the combination with rails, 10 of splice bars bracing the sides of said rails, one of said splice bars having the outer vertical face thereof provided with an enlargement, said enlargement having the top and end edges thereof beveled and the lower edge spaced from the lateral portion of said splice bar to form a longitudinal groove, 15 said splice bar and said enlargement having openings formed therein, said enlargement having vertical slots intersecting said open-

ings, bolts adapted to extend through said splice bars and said rails, said bolts having the ends thereof provided with slots adapted to vertically align with the slots of said 20 enlargement, and keys driven in the slots of said enlargement and said bolts and adapted to have the ends thereof spread in the groove formed by the bottom edge of said enlargement and the lateral portion of 25 the splice bar, substantially as described.

In testimony whereof I affix my signature in the presence of two witnesses.

ABRAHAM R. BERRYMAN.
